UNITED STATES PATENT OFFICE.

WARREN M. SMITH, OF MOORE, AND SAMUEL M. CURWEN, OF HAYEFORD, PENNSYLVANIA,
ASSIGNORS TO THE J. G. BRILL COMPANY, OF PHILADELPHIA, PENNSYLVANIA, A COR-
PORATION OF PENNSYLVANIA.

PASSENGER-CAR.

No. 901,787.

Specification of Letters Patent.

Patented Oct. 20, 1908.

Application filed May 28, 1908. Serial No. 435,436.

To all whom it may concern:

Be it known that we, WARREN M. SMITH and SAMUEL M. CURWEN, citizens of the United States, residing in Moore, Pennsylvania, and Haverford, Pennsylvania, respectively, have invented certain Improvements in Passenger-Cars, of which the following is a specification.

Our invention relates to certain improvements in passenger cars of the type in which passengers pay their fares on entering the car.

The object of our invention is to provide for the inclosing of the platform by a sliding and pivoted door on one side, and a sliding door on the opposite side; the doorways leading from the platform to the body of the car being always open.

In the accompanying drawings:—Figure 1, is a sectional plan view of one end of a car illustrating our invention and showing the doors closed; Fig. 2, is a similar view of part of the platform showing the doors open; Fig. 3, is a sectional plan view of one side of the car showing the sliding door partly open; Fig. 4, is a sectional view showing the lower guide rail of the sliding door illustrated in Fig. 3; Fig. 5, is a sectional elevation on the line 5—5; Fig. 2; and Fig. 6, is a perspective view of the detachable seat which we preferably use when the doors are closed as in Fig. 1, when the platform is at the forward end of the car.

F is the body of the car.

35 E is the platform.

F', F' are the corner posts and in the transverse partition G are the doorways g, g', separated by the panel g². These doorways are preferably not provided with doors, as in this construction of car the platform is entirely closed.

E' is the vestibule framing inclosing the outer end of the platform, and E² is a fixed double panel providing a slideway e² for the sliding door I, which is adapted to close the exit passage e¹ at one side of the platform. The opposite side e² of the platform has two doorways e³, e⁴ separated by a post E³.

50 A is a sliding door arranged to close the passageway e³ and B is a door pivoted at b to the post and arranged to close the passageway e⁴.

Extending from a point opposite the post

E³ to one side of the panel g² of the partition 55 G is a guard D in the form of a rail; the rail being mounted on posts d, d' and secured firmly to the partition in the present instance. The post d is a distance from the post E³ at the side of the platform so as 60 to allow for the free passage of a person between the posts when the platform is at the forward end of the car, and the door B is of such a width that when it is turned to the position shown in Fig. 2 it will close the 65 steps between the posts E³ and d so as to divide the platform into ingress and egress sections; the rail D forming a continuation of this partition.

The sliding door A is hung from a rail a 70 by grooved wheels a' swiveled to the door; the rail being bent to conform to the shape of the vestibule framing of the car. The lower end of the door is held in place by a fixed rail a² with which engages a hook a³ 75 on the edge of the door so that by simply pushing the door back it will readily pass around the groove, as shown in Fig. 3, and assume the position shown in Fig. 2; being out of the way of passengers entering the 80 car.

In some instances it may be desirable in addition to the door B to continue the rail D to the post E³, as shown by dotted lines in Fig. 1, and this rail may be hinged so as to 85 drop and leave a clear opening when the platform is at the forward end of the car.

C is a detachable seat of the form shown in Fig. 6, having lugs c, c which engage the lower rail a² by which the lower portion of 90 the door A is guided, or it may engage independent brackets secured to the vestibule framing as desired. Pivoted to the underside of the seat are supporting legs which are bent in the present instance as shown, 95 and connected by a rod e² so that they can be folded under the seat when it is desired to remove the seat from the side of the car or transfer it from one end of the car to the other, as the seat would only be used when 100 the doors are closed and the platform is at the forward end of the car.

It will be seen from the above description that we can construct a car of the type in which passengers pay their fares on entering 105 the car, dividing the platform into ingress and egress passageways by a rail D and by the pivoted door closing the egress

passageway at the edge of the platform, as the moment the door is open to allow a passenger to leave the car at the rear platform the door becomes part of the 5 guard or partition separating the egress section from the ingress section of the platform; a sliding door being used for the ingress section which is independently operated and is pushed out of the way along- 10 side of the permanent vestibule casing at the end of the platform.

The conductor is located in the egress section of the platform directly back of the rail D, so that he can control the admission 15 of passengers to the body of the car and yet operate the doors when necessary.

We claim:—

1. The combination in a passenger car, of a body portion, a platform, ingress and 20 egress passageways at one side of the platform, the egress passageway being nearest the body of the car, a post at the edge of the platform separating the two passageways, a door hinged to the post and ar- 25 ranged to close the egress passageway, a sliding door, and guides for the door, said door being arranged to slide against the end of the vestibule framing.

2. The combination in a passenger car, of 30 a body portion, a platform, vestibule fram- ing at one end of the platform, a post at one side of the platform separating the ingress and egress passageways leading to the platform, a sliding door closing the ingress 35 passageway, a pivoted door closing the egress passageway, a guard at the center of

the platform and forming with the door closing the egress passageway when open a partition separating the egress section of the platform from the ingress section. 40

3. The combination in a passenger car, of a body portion, a platform, vestibule fram- ing at the end of the platform, a transverse partition separating the body of the car from the platform, ingress and egress pas- 45 sageways in said partition, a fixed section separating the said passageways, a rail ex- tending from one side of the fixed section over the platform, a post at one side of the platform, a pivoted door hung to the post 50 and closing one of the passageways, said door when open forming with the rail a par- tition separating the ingress section of the platform from the egress section, and a sliding door arranged to close the other pas- 55 sageway at the side of the car.

4. The combination in a passenger car, of a platform, ingress and egress passageways at the side of the platform, doors closing 60 said passageways, a detachable seat section having lugs engaging the projections on the fixed portion of the car and having col- 65 lapsible leg sections, said seat extending along the inner side of the two doors.

In testimony whereof, we have signed our 65 names to this specification, in the presence of two subscribing witnesses.

WARREN M. SMITH.
SAMUEL M. CURWEN.
